UNITED STATES PATENT OFFICE.

GEORGE SCHUBERT, OF WALNUT SPRINGS, TEXAS.

GRAIN-CONVEYER FOR BINDERS, &c.

SPECIFICATION forming part of Letters Patent No. 446,473, dated February 17, 1891.

Application filed May 5, 1888. Serial No. 272,904. (No model.)

To all whom it may concern:

Be it known that I, GEORGE SCHUBERT, a citizen of the United States, residing at Walnut Springs, in the county of Bosque and State 5 of Texas, have invented certain new and useful Improvements in Grain-Conveyers for Binders and Operating Mechanism Connected Therewith; and I do hereby declare the following to be a full, clear, and exact description of 10 the invention, such as will enable others skilled in the art to which it appertains to make and use the same.

This invention relates to grain-conveyers used in connection with grain binders and harvesters; and it consists of an improved construction for conveyers and the details of the same, and operating mechanism, as herein-after described and claimed.

In the accompanying drawings, Figure 1 is 20 a plan view showing a grain-conveyer with my improvements applied to a harvester-platform. Fig. 2 is a side view, partly in section, of the conveyer and connecting parts. Fig. 3 is a perspective view of the conveyer-head closed. Fig. 4 shows a plan of the under side of the conveyer-head.

Referring to the drawings, A designates the platform, which is formed of upper and lower plates of sheet-iron, which are braced by intervening strips, to which the plates are secured, two of said strips forming walls of the 30 passage of the conveyer. Openings are made in the upper surface of the platform for the purposes of the conveyer and the devices carried by it.

B indicates a block, forming with its attachments the head of the conveyer, which is moved by an endless chain a, which passes over sprocket-wheels c c', the said head moving 40 in a passage between two walls m² m⁴ and extending upwardly through a slot b in the upper plate of the platform. The notches or openings d are formed in the upper plate of the platform on opposite sides of slot b at the 45 point from which the conveyer-head moves near the outer edge of the platform, the metal being bent down, as seen at e, at the inner side of the notches to form guides, for the purpose hereinafter stated. The notches or openings d' are formed in the upper plate near the inner edge of the platform, the metal being bent up at the outer side of the notches, as

seen at e', to form guides at a point near the forward end of the passage of the conveyer.

The block B is provided with two pivoted 55 arms f, the pivoted ends of said arms being provided with toothed segments c² for engagement with each other, so that when one of said arms is turned laterally outward the other arm is turned laterally in the opposite 60 direction, as shown in the drawings. To the outer ends of arms f are hinged the extensions g, so that the latter may rise, and to the outer ends of these extensions are loosely connected the rods h at a suitable distance from the 65 hinge-connection of parts f and g. The said rods h are also connected at their other ends with the block B at i i, being a suitable distance forward from the pivots of arms f.

C indicates a central lever, which is pivoted 70 in bearings i' on the block B, the lower part of said lever being curved and extending through a slot m in the block and carrying on its end a cross-piece m', on the ends of which are placed rollers h'. The upper part 75 of lever C is straight, and its upper end is pivoted to an extension n between the ends of the latter, said extension n having a curved point, the rear end of said extension being loosely connected by a link n' with block B 80 near its rear end. Anti-friction rollers n² extend laterally from the sides of block B within said passage and move against the upper metal plate below the metal each side of the slot b and serve to keep the block in position. 85

On the pivot of one of the arms f and under the block B is loosely placed a roller n³, which serves to prevent the block B from rubbing against the adjacent wall m². An arm n⁴ is fastened to the lower end of said 90 pivot and extends to the opposite side of the passage, said arm having an anti-friction roller o at its outer end. As seen in Fig. 4, the arm n⁴ extends into a recess m³ of the opposite side wall m⁴ of the passage. 95

C' indicates an elbow-lever, which is pivoted in the platform A in position to be engaged by the conveyer-head as it moves forward, said lever being connected by a rod o' with the hinged butter-board D, as shown in 100 Fig. 1. C² is another pivoted lever having an arm o², said lever being also in position to engage with the conveyer-head in its movement. The lever C² is extended beyond its

pivot and linked to the lower end of an upright pivoted lever C^3 , the bent upper end of which is connected with the lower end of a lever C^4 , which is fast on a shaft p . The said shaft carries an arm p^4 , which is connected by a rod s^6 with an arm r^3 , pivoted at its lower end to some support. Through this arm r^3 passes a shaft s^7 , which also passes through a sleeve s^8 , pivoted at s^9 in a bracket s^{10} . The inner end of the shaft s^7 carries a gear s , which always meshes with a gear c^3 on a transverse shaft c^6 , carrying pulleys c' , over which run the chains a . The outer end of said shaft s^7 carries a bevel-gear s' , which may be thrown into engagement with either of the bevel-gears s^2 or s^3 by movement of the arm or bearing r^3 , carrying the sleeve s^8 , through which passes the shaft s^7 . The arm r^3 , as above stated, is connected by the rod s^6 with the outer end of the arm p^4 , whose inner end is fast on the shaft p . Said shaft is automatically turned in one direction by the striking of the head-block B against the lever C^2 , which turns the upright lever C^3 , and that in turn turns the lever C^4 , which is fast on the shaft p . The latter is turned in the opposite direction, as well, by the draw-rod M .

The levers C' and C^2 and the mechanism with which the outer ends of said levers are connected are the same as those shown and described in my application for a patent for a grain-binder, Serial No. 272,905, filed May 5, 1888.

The stops p' are pivoted in the platform in vertical position, in which they are sustained by springs r , one stop being located on each side of the slot b near its inner end. The object of these stops is to prevent the passage of any straggling grain which falls on the conveyer-chain behind the conveyer and might be carried along by the chain. The stops yield to the pressure of the loaded conveyer as it passes forward; but after it has passed they are raised by their springs and retain the straggling grain for the next operation of the conveyer. A rod r' is connected at one end with the lever C^2 and extends along the conveyer-passage, and has its end r^2 bent and in position to catch against the block B on the return movement of the conveyer, thus drawing lever C^2 , as hereinafter stated.

E indicates a fixed angular piece or expander with its point in position at the outer end of the slot b . The sides of this expander 55 diverge from its point, and its upper corner or angle also rises from said point toward its base, whereby as the conveyer-head moves to the outer end of its passage, its arms f extending forwardly, said arms and also central lever C having been closed, the arms f impinge against the opposite sides of the expander E and are thus somewhat expanded for the next forward movement of the conveyer, and the forward end of lever C 65 raised by said expander so that it assumes the position shown in Fig. 2. The conveyer is started in its forward movement by the

driver drawing-rod M , by which the shaft s^7 of wheel s' is moved, and wheel s' is turned into engagement with pinion s^2 on the power-shaft and through intervening mechanism imparts motion to the shaft of the sprocket-wheel c' , the conveyer being thus drawn forward, all as described above. As the conveyer-head starts on its forward or inward movement, the arm n^4 , extending into recess m^3 at one side and near the outer end of the passage, remains therein until the conveyer has passed, drawing the arm with it, the movement of the arm causing the engaging arms f to turn outward in opposite directions, as seen in Fig. 1, and the hinged extensions g are raised by the rods h , by which the extensions are connected with the block B . At the same time the central lever C is raised by the cross-piece m' coming in contact with guides e , which causes the cross-piece to rise, and thus bring the straight part of lever C to a vertical position. A curved link i^2 allows the cross-piece m' to rise without raising the chain. This link is rigidly attached at one end to the block B and linked at its other end to the chain, between which ends it curves upwardly, whereby said movement of the cross-piece m' is permitted, as shown in Fig. 2. The extension n , carried by C , is raised by the connecting-rod n' . The conveyer-head, with its arms extended, moves forward, conveying the grain to the compressing devices, and as it moves along actuates lever C' , by which the compressing devices are started. When near the end of its forward movement it strikes the lever C^2 , thereby throwing gear s into engagement with the other bevel-gear on the driving-shaft, and thus reversing the movement of the sprocket-wheel shaft and the movement of the conveyer-chain. As the conveyer commences its return movement the arm n^4 enters the recess m^5 at one side and near the inner end of the passage, and as this arm is keyed to the pivot of one of the arms f and moves in unison therewith its turning causes the arms f to turn backward, thus folding down the extensions g and connecting-rods h . The cross-piece carried by lever C falls through the opening d' , causing lever C and connections to fold down, as shown in Fig. 3, and the conveyer-head is moved back to its starting-point with its parts folded so that it can pass underneath the grain on the platform. As the conveyer-head approaches the end of its return movement the block B strikes the bent end r^2 of rod r' , connected with lever C^2 , thus drawing lever C^2 , which is connected with lever C^3 , which is connected with lever C^4 . The lever C^4 , being fast on a shaft p , turns said shaft, and through arm p^4 , which is connected by a rod s^6 with the movable bearing r^3 of the shaft s^7 of wheel s and pinion s' , draws the movable bearing, and the pinion s' is thrown out of engagement with the pinion s^3 , whereupon the movement of the conveyer ceases, all as more fully described above.

A slot b' , similar to b , is made in the platform, with similar appurtenances and levers $c^3 c^4$, and the conveyer-head may be transferred to and arranged in said slot for operation when long grain is to be bound. For such purpose an extension H is usually provided for the platform, and levers c^3 and c^4 may be connected with C' and C^2 , respectively, by links c^9 , as indicated in Fig. 1, for imparting motion.

In constructing the platform the lower plate of the platform may be riveted to the lower face of the finger-bar and the upper plate to the upper face of the finger-bar; or they may be connected in any other suitable manner, wooden fillings W being put in between the plates to form braces for the platform and walls for the passage-way of the conveyer.

20 I claim—

1. In a grain-conveyer, the combination, with the platform A , having a slot b and parallel walls $m^2 m^4$ on the sides thereof, one of said walls being provided with a recess m^3 , of 25 the conveyer-block B , moving between said walls, an arm f , mounted on a vertical pivot in said block, and an arm n^4 , rigidly connected to the pivot of said arm f and having a friction-roller o at its free end, adapted to engage said recess, as and for the purpose set forth.

2. In a grain-conveyer, the combination, with the platform A , having a slot b and parallel walls $m^2 m^4$ on the sides thereof, one of 35 said walls being provided with a recess m^3 , of the conveyer-block B , moving between said walls, arms f , mounted on vertical pivots in said block, intermeshing toothed segments c^2 at the inner ends of said arms, and an arm n^4 , 40 rigidly connected to the pivot of one of said arms and having a friction-roller o at its free end, adapted to engage said recess, as and for the purpose set forth.

3. In a grain-conveyer, the combination, 45 with the platform A , having a slot b , with parallel side walls $m^2 m^4$, and the conveyer-block B , moving between said walls, of the arms f , mounted on vertical pivots in said block, intermeshing segments c^2 at the inner 50 ends of said arms, means, substantially as described, for throwing said arms outwardly at the proper time, extensions g , hinged to the outer ends of said arms, and rods h , linked at their ends to said extensions and 55 to the block B , all as and for the purpose set forth.

4. In a grain-conveyer, the combination, 60 with the slotted platform A , the conveyer-block B , moving in the slot therein, the arms f , mounted on vertical pivots in said block, and means for operating said blocks, of the wedge-shaped piece E , mounted upon the platform A at the end of the slot therein and adapted to separate the outer ends of said 65 arms f , as and for the purpose set forth.

5. In a grain-conveyer, the combination, 65 with the platform A , a slot b therein, provided

with side tracks having openings $d d'$ through the platform at the opposite ends of said tracks, and the conveyer-block B , moving on 70 said tracks, of the lever C , pivoted in said block and having a curved lower portion, a cross-piece m' at the end of said curved portion, and friction-rollers h' on the extremities of said cross-piece, moving on said tracks as and for the purpose set forth.

6. In a grain-conveyer, the combination, 75 with the platform A , a slot b therein, provided with side tracks having openings $d d'$ through the platform at the opposite ends of said tracks, and the conveyer-block B , moving on said tracks and having a slot m in its body, of the lever C , pivoted in slot m and having a curved lower portion, the cross-piece m' 85 at the end of said curved portion, its ends moving on said tracks and adapted to pass through said openings, an extension n , pivoted between its ends to the end of said lever C , and a rod n' , pivotally connecting the end 90 of said extension with the conveyer-block, all as and for the purpose set forth.

7. In a grain-conveyer, the combination, 95 with the platform A , having the slot b , with overhanging side walls, the latter having notches d near the ends of the slot, of the endless chain a , moving in said slot and having an upwardly-curved link projecting through it, the conveyer-block B in the chain adjacent said link, the lever C , pivoted in 100 said block, and the cross-piece m' at one end of said lever, passing through said notches and standing within said link when raised, substantially as described.

8. In a grain-conveyer, the combination of 105 the platform A , having a slot b , parallel walls $m^2 m^4$ at the sides thereof, one of said walls being provided with a recess m^3 , and tracks on the inner faces of said wall, with the conveyer-block B , having friction-rollers n^2 moving 110 upon said tracks, the arms f , mounted on vertical pivots in said block and having intermeshing toothed segments c^2 at their inner ends, extensions g , hinged to the outer ends of said arms and linked to the block, means, 115 substantially as described, for throwing said arms outward, with the lever C pivoted in said block, an extension n , pivoted to said lever and adapted to be thrown upward thereby, and means, substantially as described, 120 for operating said lever, all as and for the purpose set forth.

9. In a grain-conveyer, the combination, 125 with the slotted platform A and the conveyer-block B , moving in the slot therein, of the lever C^2 , pivoted to said platform with its free end in the path of said block, the upright pivoted lever C^3 , linked to the other end of said lever C^2 , the lever C^4 , keyed on a shaft p and having one end connected with the upper end of the upright lever C^3 , the arm p^4 , fast on said shaft p , the shaft c^6 , driving endless chains a for moving said block B and having a gear c^5 , the gear s in constant mesh with 130

said gear c^5 , mechanism for driving said gear s in either direction, and reversing devices for said mechanism, substantially as described, connected with said arm p^4 , all as 5 and for the purpose set forth.

10. In a grain-conveyer, the combination, with the slotted platform A and the conveyer-block B, moving in the slot therein, of the lever C^2 , pivoted on said platform with its 10 free end in the path of said block, the upright pivoted lever C^3 , linked to the other end of said lever C^2 , the lever C^4 , keyed on a shaft p and having one end connected with the upper end of the upright lever C^3 , the arm p^4 , 15 fast on said shaft p , the shaft c^6 , driving endless chains a for moving said block and having a gear c^5 , the gear s in constant mesh with said gear c^5 , the sleeve s^8 , surrounding the shaft s^7 of said gear s and pivoted midway of its length, a beveled gear s' on the other end 20 of said shaft s^7 , adapted to mesh with either of the gears s^2 s^3 on the main driving-shaft, and an arm r^3 , having a stationary pivot at one end and linked at its other end to the free end of said arm p^4 , the sleeve s^8 , passing 25 through said pivoted arm r^3 , and the whole operating substantially as hereinbefore set forth.

11. In a grain-conveyer, the combination, with the slotted platform A and the convey-

er-block B, moving in the slot therein, of the lever C^2 , pivoted to said platform with its free end in the path of said block, the upright 30 pivoted lever C^3 , linked to the other end of said lever C^2 , the lever C^4 , keyed on a shaft p and having one end connected with the upper end of the upright lever C^3 , the arm p^4 , 35 fast on said shaft p , the shaft c^6 , driving endless chains a for moving said block and having a gear c^5 , the gear s in constant mesh with said gear c^5 , the sleeve s^8 , surrounding the shaft s^7 of said gear s and pivoted midway of its length, a beveled gear s' on the other end 40 of said shaft s^7 , adapted to mesh with either of the gears s^2 s^3 on the main driving-shaft, and an arm r^3 , having a stationary pivot at one end and linked at its other end to the free end of said arm p^4 , the sleeve s^8 , passing 45 through said pivoted arm r^3 , and the whole operating substantially as hereinbefore set forth.

In testimony whereof I have affixed my signature in presence of two witnesses.

GEORGE SCHUBERT.
